(Cl. D48—20)

FIG. 1.

Des. 196,136

PAGE 2

FIG.2.

FIG.3.

FIGURE 1 is a perspective view of a floodlight, showing our new design.

FIGURE 2 is a fragmentary front elevational view of the floodlight shown in FIGURE 1.

FIGURE 3 is a partial sectional view taken on line 3—3 of FIGURE 2.

The rear of the reflector housing is substantially plain, and the rear of the reduced member below the reflector is substantially the same in appearance as the front.

The dominant features of our design reside in the portions shown in full lines.

We claim:

The ornamental design for a floodlight, as shown and described.
